PROTECTIVE EQUIPMENT

Allan R. Brown, Elmhurst, Ill., assignor to General Electric X-Ray Corporation, Chicago, Ill., a corporation of New York

Application October 15, 1945, Serial No. 622,457

2 Claims. (Cl. 250—93)

1

The present invention relates in general to electronics and has more particular reference to the operation and control of X-ray generators.

An X-ray generator, as is well known, functions as a result of electron impingement upon a suitable target, electrons being emitted at the cathode of the generator and directed therefrom upon the target, which comprises the anode of the generator. Impingement of electrons on the anode is caused by the application of electrical potential between the electron emitting cathode and the anode. Current, also, is caused to flow between the anode and cathode as a result of the travel of electrons from the cathode to the target. Electrical power for the operation of the generator is ordinarily supplied through a power circuit, connected with the anode and cathode of the generator and including the secondary winding of a transformer.

Operation of the generator may be controlled by varying the electron emissivity of the cathode or by varying the potential applied between the anode and cathode, or by varying both cathode excitation and anode-cathode potential.

For any selected value of cathode excitation and anode-cathode potential, a corresponding current flow will occur in the anode-cathode circuit, current flow being measurable as a function of anode-cathode potential, and increasing with potential, and vice-versa. It is, of course, desirable, if not essential, to provide means responsive to overload conditions and operable either to indicate such conditions or to disable or otherwise perform protective functions with respect to the X-ray generating equipment. To this end, suitable indicating or control apparatus may be provided to operate in response to overload conditions represented by excessively high current flow in the anode-cathode circuit. Since, however, the generator, when operating at full load, normally requires a relatively heavy current flow, of the order of two or more times the current flow encountered when the generator is in operation under no load or small load conditions, it is obvious that a current responsive device adjusted to accommodate the relatively heavy full load current flow may fail to operate under overload conditions occurring when the generator is in operation under light load.

It is an important object of the present invention to provide current responsive apparatus which will operate in response to overload conditions whether such conditions occur in the generating system when in operation under any load

2

conditions within the range of the equipment concerned; a further object being to provide current responsive control apparatus in which the current response of the apparatus varies as a function of the potential prevailing in the circuit with which the apparatus is associated.

Another important object is to provide control means of the character mentioned embodying a saturable core transformer, and to utilize the transformer for the performance of an indicating or control function, in response to over-current conditions in a circuit with which the transformer is associated; a further object being to vary the magnetic saturation of the transformer as a function of the prevailing circuit load so that the device may have substantially the same response for all load values from zero to full load.

Another important object is to utilize a saturable transformer for the purpose of monitoring a power circuit such as that employed in energizing an X-ray generator, and to vary the saturation of the transformer as a function of the load of said circuit, whereby to actuate an operable control device, such as an associated relay, in response to over-current conditions in said circuit.

The foregoing and numerous other important objects, advantages, and inherent functions of the invention will become apparent as the invention is more fully understood from the following description, which, taken in conjunction with the accompanying drawings, discloses a preferred embodiment of the invention.

Referring to the drawing:

The single figure is a diagrammatic representation of an X-ray generator and associated control equipment embodying the present invention.

To illustrate the invention, the drawing shows an X-ray generator 1 having a cathode 2 and an anode 3, the generator being of the type designed for operation at high voltages of the order of one million volts, and more, applied between the anode and cathode. Power for energizing the generator is supplied through a transformer 4 having a primary winding 5 and a secondary winding 6. The secondary winding includes a portion 7 which is connected with the cathode of the generator, through an adjustable current flow control device 8, whereby to energize the cathode to render the same electron emissive. The secondary winding of the transformer also includes a winding portion 9, which is connectible between the cathode 2 and the anode 3. To this end, the anode 3 may be grounded, through a

suitable resistor 10. The high voltage end of the winding 9 may be connected with the cathode while its low voltage end may be connected to ground, through one or other of the sensitive microammeters 11, by means of relay switches 12, in order to complete the anode-cathode circuit of the generator.

Specifically, the high voltage circuit extends from the cathode of the generator through the transformer winding 9 thence through a filter 13 adapted to by-pass the alternating current component directly to ground while delivering the direct current component to a normally closed switch 14. The switch 14 may, of course, be a normally open switch adapted to be held closed so long as its operating solenoid 15 is energized. As shown, however, the switch 14 is a normally closed switch which is operatively associated with and closable by a solenoid 15 when energized. From the switch 14 the circuit extends to a pair of relay switches 16. The switches 16 are interlocked so that one is open when the other is closed, and vice-versa, one switch being normally open and the other normally closed, and both being operatively associated with a solenoid 17. One of the switches 16 is connected, through one of the meters 11 and preferably through a suitable ground connection and the resistor 10, to the anode 9 of the generator; and the other switch 16 is likewise connected, through the other meter 11, to the anode of the generator.

Power is delivered to the primary winding 5 of the transformer 4, through suitable supply and control circuit means 20, from an alternating current generator 21. This alternator 21 has a field winding 22 energized through suitable circuits 23. The field energizing circuits 23 are controlled by relay switches 24 operable by an associated actuating solenoid 25. The switches 24 are preferably normally open switches and the solenoid 25 may be connected to a source of energizing power 26, in order to maintain the coil energized and the switches 24 closed, whereby to energize the field winding 22 of the alternator 21, thereby causing it to supply power to the primary transformer winding 5, through the power circuit conductors 27, an adjustable choke 28 being included in the circuit for the purpose of providing unity power factor operation of the alternator. A condenser 34 also may be connected across the power circuit to introduce desired reactive characteristics.

In the event of an overload in the anode-cathode circuit of the generator, the control means 20 may operate to short circuit the solenoid 25 thereby allowing the switches 24 to open, thus reducing or cutting off the power supplied by the alternator to the primary winding of the transformer.

Alternately, the switches 24 may be normally closed and the protective system may be connected to energize the solenoid 25 to open them, or the system may be utilized to accomplish any other desired control function.

To this end, the protective system 20 preferably comprises a saturable core transformer 30 having a pair of lateral legs 29 and a central or common leg. The transformer has a pair of current windings 29' inductively coupled with the legs 29 and electrically connected in the circuit 27 between the alternator 21 and the primary winding 5 of the transformer 4. The saturable core transformer also includes a saturating coil 32 inductively coupled with the common leg of the transformer, which common leg has

a part forming a magnetic loop or circuit with one of the legs 29, and another part forming a separate magnetic circuit with the other leg 29. This saturating coil 32 is connected in parallel relationship with respect to an adjustable resistor 33, said saturating coil and resistor being interposed in series relationship in the conductor 19 between the meters 11 and ground, whereby the saturation of the transformer is a proportional function of the direct current component of energy in the anode-cathode circuit of the X-ray generator 1. The resistor 33, of course, is provided for adjusting the degree of saturation of the transformer 30.

Inductively coupled with each leg 29 of the transformer 30 is a coil 31, the two coils 31 being connected in series with each other and with the actuating coil 36 of a preferably normally open relay switch 35 which, as shown, may be connected across the actuating coil 25 of the switch 24.

Under normal operating conditions, the current flow in the windings 29' of the saturable transformer 30 will develop insufficient current in the windings 31 to energize the winding 36 sufficiently to close the normally open switch 35. Consequently, the alternator 21 will function to energize the primary winding of the transformer 4. In the event that an overload condition should develop, the increased current flow in the windings 29' will actuate the switch 35 through the coil 33 and the windings 31 of the saturable transformer. Since the saturation of the transformer 30 is accomplished as a function of the current flowing in the secondary winding of the power transformer 4, the response of the switch 35 can be made dependent upon the energy delivered in the anode-cathode circuit of the X-ray generator; hence the response of the control will be a function of the secondary load of the transformer 4. If said transformer 4 be lightly loaded, the current flow in the windings 29' will likewise be light, but the control system will function to close the switch 35 in response to any excess current flow in the windings 29'. At full load, a corresponding relatively large current will flow in the windings 29' without, however, causing the switch 35 to close, the same being accomplished by the change in saturation of the transformer 30 due to the application of full load conditions in the winding 32. Any increase in current in the windings 29' above normal full load current, however, will cause closure of the switch 35 and thereby accomplish the protective function of the device.

The utilization of the anode-cathode current of the X-ray generator for the purpose of saturating the core of the transformer 30 will result in keeping the voltage applied across the coil 36 substantially constant throughout the operating range of the device from zero to maximum anode-cathode current in the X-ray generator at full voltage. When properly adjusted, the relay 35 will not operate so long as the current in the primary transformer circuit 27 is normal, within the operating range of the X-ray generator, but the relay will operate to disable or reduce the energy output of the alternator 21 whenever overload conditions are encountered.

It is thought that the invention and its numerous attendant advantages will be fully understood from the foregoing description, and it is obvious that numerous changes may be made in the form, construction and arrangement of the several parts 75 without departing from the spirit or scope of the

invention, or sacrificing any of its attendant advantages, the form herein disclosed being a preferred embodiment for the purpose of illustrating the invention.

The invention is hereby claimed as follows:

1. A control system for an X-ray generator having a cathode and a grounded anode, comprising an alternator having a field winding, circuit means for applying, between said anode and cathode, electrical energy delivered from said alternator, including a voltage step-up power transformer having a high voltage secondary winding connected with said cathode, and a primary winding, a saturable core relay transformer having a pair of circuit forming legs, each forming a portion of a separate magnetic circuit, and a common leg included in both of said magnetic circuits, a pair of power coils, each inductively coupled with a corresponding one of said circuit forming legs, said power coils being interconnected in series with said primary winding and said alternator, to form said circuit means, a saturating winding inductively coupled with said common leg, filter means to connect said secondary winding of the power transformer to ground through said saturating winding, whereby to energize the same in proportion to the uni-directional component of electrical current delivered between said anode and cathode, a pair of actuating windings inductively coupled, one with each of said magnetic circuits, and means controlled by current flow in said actuating windings, for variably energizing said field winding of the alternator.

2. A control system for an X-ray generator having an anode and a cathode, comprising an alternator having a field winding, circuit means for applying, between said anode and cathode, alternating current electrical power delivered from

said alternator, including a voltage step-up power transformer having a high voltage secondary winding interconnected with said anode and cathode, and a primary winding, a saturable core relay transformer having a pair of circuit forming legs, each forming a portion of a separate magnetic circuit, and a common leg included in both of said magnetic circuits, a pair of power coils, each inductively coupled with a corresponding one of said circuit forming legs, said power coils being interconnected in series with said secondary winding and said alternator in said circuit means, a saturating winding inductively coupled with said common leg, means connected with the high voltage secondary winding of said power transformer and with said saturating winding for applying uni-directional energizing current in said saturating winding in proportion to the uni-directional component of electrical current delivered between said anode and cathode, a pair of actuating windings inductively coupled, one with each of said magnetic circuits of the relay transformer, and means controlled by current flow in said actuating windings for variably energizing said field winding of the alternator.
